UNITED STATES PATENT OFFICE.

FRANK W. JENKINS, OF BROOKLYN, NEW YORK.

APPARATUS FOR CUTTING PACKINGS.

SPECIFICATION forming part of Letters Patent No. 288,839, dated November 13, 1883.

Application filed August 14, 1883. (No model.)

To all whom it may concern:

Be it known that I, FRANK W. JENKINS, a citizen of the United States, residing in the city of Brooklyn, county of Kings, and State 5 of New York, have invented certain new and useful Improvements in Apparatus for Cutting Packings, fully described and represented in the following specification and the accompanying drawings, forming a part of the same.

10 This invention relates to an apparatus for cutting washers and packing-rings from sheets of pasteboard, rubber, and other similar materials, and for other analogous purposes.

15 It is well known to those familiar with the art that washers and packings made of these and similar materials are used in such large quantities in connection with steam, hydraulic, and other similar machinery that any means by which the labor and expense attending 20 their production can be reduced is a matter of considerable importance. The great variety of sizes and shapes in which these washers and packings are required makes it impracticable to provide steel cutting dies or punches 25 for their production, as such tools are so expensive that the large number which would be required to produce all the necessary sizes and shapes would make the outlay too great. It has therefore been customary to cut these 30 washers and packings by hand, which method not only involves great labor and annoyance, but results in the production of irregular and imperfect work.

35 It is the object of the present invention to provide a simple tool or apparatus by which these washers and packings in any size or shape can be rapidly and accurately cut from sheets of pasteboard, rubber, or any similar suitable material, and which shall also be so 40 inexpensive that it will be entirely practicable to provide a separate apparatus for each size and shape required.

45 To these ends the invention consists in various details of construction and combinations 50 of parts in an apparatus for accomplishing this result, all of which will be hereinafter fully explained and particularly pointed out.

55 In the accompanying drawings, Figures 1 and 2 are central vertical sections of the two 50 parts of an apparatus embodying the present invention for producing a round washer or packing. Fig. 3 is a plan view of Fig. 1, the

male member of the punch being removed. Figs. 4 and 5 are views illustrating the steps or operations involved in the production of 55 such a packing. Figs. 6 and 7 are central vertical sections of the two parts of an apparatus for producing a packing of irregular form. Fig. 8 is a plan view of the male member of the punch shown in Fig. 6. Fig. 9 is a plan 60 view of Fig. 6, with the male member of the punch removed. Fig. 10 is a plan view of Fig. 7, the male member of the punch being removed. Fig. 11 is a view similar to Fig. 6, but showing the male member of the punch in 65 a different position; and Figs. 12 and 13 are views illustrating the steps or operations involved in the production of such a packing.

Referring to said figures, it will be seen that the apparatus complete consists of two separate and independent punches, A, B, the first being adapted to cut the disk or blank to form the washer or packing, and the second to cut the required openings therein. Each of these punches consists of two principal parts—the 70 female member or punch proper, a, and the female member having the die-opening b, the female member or die being in turn composed of two parts, c d, between which the material to be cut is held. 75

The die-opening b of the punch A is made of the size and shape of the outside periphery of the washer or packing which is to be produced—as, for example, round, as shown in Figs. 1 and 3, or oval, as shown in Figs. 6 and 85 9—the punch or male member a being an exact counterpart thereof, and fitting snugly therein. The part c rests upon the part d, and is held in proper register therewith by two or more dowel-pins, e. 90

The operation of the punch A is as follows: The parts a c being removed from the part d, the sheet of material f, from which the washer or packing is to be cut, is impaled upon the pins e, and the part c is placed in position, the 95 weight of the part c serving to hold the material f down firmly like a drum-head, and aid the cutting of the same by allowing no opportunity for the material to change its position. The male member a is then placed in the die-opening and allowed to rest upon the sheet f. When the parts are in this position, by striking the punch a a sudden blow with a mallet 100 or hammer it will be forced downward, and as

the abrupt edges of the parts *a* *d* pass each other the disk or blank *g* will be sheared or broken out of the sheet *f*, as shown in Figs. 4, 11, and 12. It is found in practice that the 5 cut thus made, even when the sheet *f* is of the toughest material, will not be ragged, but will be as abrupt and clean as if made by knife-edges.

The die-opening *b* of the punch *B* is made 10 of the size and shape of the inner periphery of the washer or packing, which is round, as illustrated in the present case, but may of course be oval, square, or of any other required form, the punch or male member *a* being 15 in this case, as in the case of the punch *A*, the exact counterpart of such opening, and fitting snugly therein. The part *d* is in this case provided with a recess, *h*, of the shape of the blank *g*, so that said blank will be held in 20 proper position with relation to the punch *a* and the die-opening, the part *c* being provided with a flange, *k*, which fits into said recess and holds the blank in position and the parts *c* *d* in proper register.

25 The operation of the punch *B* is as follows: The blank *g*, having been formed by the punch *A*, as just described, is placed in the recess *h* of the companion punch, *B*, and the part *c* is placed in position, as shown in Figs. 2 and 7. 30 The punch *a*, being thus placed in the die-opening and allowed to rest upon the blank *g*, is struck, as before described, which will force it downward, so as to remove the central portion, *l*, and complete the washer or packing, as 35 shown in Figs. 5 and 13.

If it is desired to provide the packing with bolt-holes, as *m*, as shown in Fig. 13, the punch *B* may be provided with supplemental punches *n* and die-openings *o*, as shown in 40 Figs. 7 and 10, by which such holes can be punched at the same time with the central opening.

Whenever the lower edge of the male member of one of the punches becomes rounded 45 from long use, the same can be readily renewed and made as good as new by simply dressing off a small portion of the face, so as to present a new edge.

When it is desired to produce a series of

packings of regularly-decreasing sizes, it will 50 not be necessary to provide two punches for each size, as in many cases the part *l*, cut from one size, will be of the proper size for forming the blank *g* for the next smaller size.

By means of a pair of punches such as just 55 described it will readily be seen that washers or packings can be easily and rapidly made, and that such packings will be smoothly and evenly cut and exactly uniform in size.

By making the punches of the construction 60 herein shown, I have found that perfect results can be attained when all of the parts are made of common cast-iron, which so reduces the cost of construction that a separate pair of punches can be provided for each size and 65 shape of packing at a comparatively trifling cost.

What I claim is—

1. The combination, with the female member made in two parts, as *c* and *d*, between which 70 the material is clamped and held while being cut, and provided with a die-opening, as *b*, extending into both of said parts, of the male cutting member arranged to reciprocate in said opening, substantially as described. 75

2. The combination, with the female member made in two parts, as *c* *d*, between which the material is clamped and held while being cut, and provided with a plurality of die-openings, as *b* *o*, extending into both of said parts, 80 of the male cutting members, as *a* *n*, arranged to reciprocate in said openings, substantially as described.

3. The combination, with the female member made in two parts, as *c* *d*, between which 85 the material is clamped and held while being cut, and provided with a recess, as *h*, and flange, as *k*, and a die-opening, as *b*, extending into both of said parts, of the male cutting member arranged to reciprocate in said opening, substantially as described. 90

In testimony whereof I have hereunto set my hand in the presence of two subscribing witnesses.

FRANK W. JENKINS.
